DRILL STEM PROTECTOR

Victor Parkin, Los Angeles, Calif.

Application June 22, 1938, Serial No. 215,157

4 Claims. (Cl. 308—4)

This invention relates to protectors for drill stems of the character employed in oil well drilling operations as a means for preventing the stem from coming into direct contact with the wall of the well bore during operation of the drill; the invention more particularly pertaining to the type of drill stem protector embodying a cushion member formed of rubber or similar resilient material, together with means for securing said cushion member to a drill stem.

The primary object of the present invention is to produce an improved construction in protectors of the above character whereby the cushion member may be easily and quickly applied to the stem without liability of accidental disengagement of the protector either during or after its application, which has been known to occur with protectors of the character now generally in use, and which accidental disengagement may result in injury to workmen or to the objectionable depositing of the protector parts in the well bore.

Another object is to provide a construction whereby the protector may be affixed to the stem by a plurality of independently operated clamping bands so as to require a minimum of effort in operating the clamping mechanism in applying the protector to the stem.

Another object is to provide a protector with a clamping means which embodies a locking element such as to insure against accidental disengagement of the clamp.

A further object is to provide a protector clamp which is so formed as to enable its operation by a tool whereby application of the protector to a drill stem and its removal therefrom is facilitated.

With the foregoing objects in view, together with such other objects and advantages as may subsequently appear, the invention is carried into effect as illustrated by way of example in the accompanying drawing, in which:

Fig. 1 is a view in side elevation of the protector showing it as applied;

Fig. 2 is a view in horizontal section taken on the line 2—2 of Fig. 1;

Fig. 3 is a view in perspective of a clamping band showing it as detached;

Fig. 4 is a perspective view of an interlocking pin for fastening the ends of the clamping band together;

Fig. 5 is a plan view depicting the manner of applying the clamping band by means of a tool

in effecting fastening of the protector cushions on a drill stem.

Referring to the drawing more specifically A indicates a fragmentary portion of a tubular drill stem and B designates generally the protector embodying the invention which is designed to be mounted on the stem A to encompass the latter at any convenient point throughout the length thereof.

10 As here shown the protector embodies a longitudinally divided cylindrical resilient shoe 6 having its inner periphery conformable to the outer periphery of the stem A to which the shoe is applied to substantially encompass the stem; the 15 shoe being so dimensioned that when applied to the stem its contiguous longitudinal margins will be slightly spaced apart to form a gap a therebetween. Formed on the outer face of the shoe 6 integral therewith is a series of circumferentially 20 extending radially projecting bumpers 7; a series of four of the bumpers being provided adjacent each end of the shoe with the bumpers at one end slightly spaced from the bumpers at the other end to provide a circumferential channel 25 C intermediate the ends of the shoe and between the bumpers on each end portion of the shoe. The adjacent bumpers of each end series are spaced apart and the adjacent ends of the bumpers contiguous the longitudinal margins of 30 the shoe are spaced apart to provide a vertical channel D therebetween. The bumpers have their outer faces formed on longitudinal curvatures which when the shoe is assembled on the drill stem the outer faces of the bumpers will 35 collectively coincide with a circle concentric with the drill stem in outwardly spaced relation thereto.

The ends of the shoe 6 are formed with outwardly projecting flanges 8 which are spaced 40 slightly from adjacent bumpers 7 and provide circumferential channels E proximate the ends of the shoe.

In carrying out the invention a series of independent clamping bands F are provided to encompass the shoe 6; one of the bands being positioned in the channel C intermediate the ends of the shoe, and a band being disposed in each of the channels E adjacent the ends of the shoe. The circumferential zones between the 50 applied bands are occupied by the bumpers 7 which extend across the width of each of such zones.

Each of the bands F is split and is formed at one end thereof with a yoke 9 the ends of the 55 side members of which are formed with elongated

loops 10 and 11 the openings of which are substantially rectangular in outline and are disposed in opposed alignment with each other. The other end of the band is formed with a loop 12 having an elongated opening of substantially rectangular outline, which loop 12 is adapted to be positioned between the loops 10 and 11 of the yoke 9 with the openings of the loops aligned to receive a pin G particularly shown in Fig. 4 by means of which the ends of the band are fastened together. The pin G is of rectangular cross section substantially conforming to the openings in the loops 10, 11 and 12, and is formed with a pointed entrant end portion 13 and an opposed headed end portion 14. A notch 15 is formed along at least one longitudinal margin of the pin which notch terminates at its ends in abrupt shoulders 16 and is of a length slightly exceeding the height of the loop 12 so that the outer end of the loop 12 may be engaged in the notch.

Provision of the plurality of independent clamping bands F enables the employment of a simple hand operated tool in effecting application of the protector to the drill stem and also its removal therefrom, and with greater facility than in other types of protectors now generally in use and particularly those requiring the employment of expanders. Such tool and the mode of application of the protector is shown in Fig. 5; the tool embodying a pair of lever-arms 17 and 18 connected by pivots 19 to the ends of a link 20, and on which arms is mounted a pair of jaws 21 and 22 which are connected to the arms by pivots 23.

The jaws 21 and 22 are formed with arcuate inner faces b of a curvature substantially conforming to that of the outer perimeter of a band F when the latter is in its applied position. The base end portions of the jaws 21 and 22 are connected by pivot pins 24 to lugs 25 and 26 affixed to the ends of a plate spring 27; which spring is adapted to be bent to conform to the band F and is arranged that when so bent it will abut a shoulder 28 on the link 20. The free ends of the jaws 21 and 22 are offset relative to each other so that they may overlap each other during application of the band F.

Mounted on the outer end of the arm 17 is a crank arm 29 which is connected to the arm 17 by a pivot 30 and which crank arm carries a loop-link 31 adapted to be engaged at its outer end with one of a series of stepped notches 32 formed on the outer end of the arm 18.

In the application and operation of the invention, attachment of the protector to the drill stem is effected by spreading the shoe along its divided portion and positioning it astride the stem to encompass the latter. The bumpers 7 and channels C and E of the shoe will then be disposed in circumferential alignment around the stem. One of the clamping bands F is then positioned astride the assembled shoe in one of the channels E or the channel C; the band being formed of spring metal and being spread at its ends to such extent as to permit its being placed around the protector shoe. The jaws 21 and 22 of the applicator tool are then engaged with the band and the arms 17 and 18 of the tool are manipulated to effect contraction of the clamping band to such extent that the loop 12 will be positioned between and in register with the loops 10 and 11, during which operation the resilient shoe 6 will be tightly compressed against the stem. The arms 17 and 18 may then be fastened against spreading to hold the jaws

21-22 and the band in place, which is accomplished by engaging the link 31 with one of the notches 32 and then manipulating the lever 29 to its locking position.

5 A pin G is then inserted through the register loops 10, 12 and 11 and positioned to bring the notch 15 thereon opposite the outer end wall of the loop 12, whereupon the tool is released to allow the band F to expand and thereby 10 cause the loop 12 to effect engagement with the notch 15 and whereby the pin G will be securely locked in place against accidental disengagement.

15 In like manner the other clamping bands are put in place so as to securely bind the protector shoe onto the stem in such fashion as not to be liable to accidental disengagement. However, by employing the applicator tool, as shown in Fig. 5, the bands F may be contracted such as to free 20 the loop 12 from the notch 15 of a pin and thereby permit withdrawal of the pin when desired to remove the protector from the stem.

25 It is manifest that when the stem is equipped with the protectors at suitable intervals throughout its length, the bumpers 7 will act when the stem is in a well bore to prevent the stem from coming into direct contact with the walls of the well bore. By providing the protector with the bumpers 7 spaced apart circumferentially of the protector ample space is provided for the flow of circulating mud along the length of the stem and well bore.

30 Owing to the fact that each of the clamping bands is independent from the others, and can 35 be independently applied, the power exerted by the workman in clamping the shoe in place is applied to a small portion of the length of the shoe at each clamping operation, hence a more forcible clamping of the bands is possible than 40 could be obtained if more than one longitudinal section of the clamping means were applied at the same time.

45 While I have described the protector as utilized in connection with a drill stem, it may also be employed on sucker rods of a pump, and in any other construction where a bumper of this character would be serviceable, and while I have shown and described a specific embodiment of the invention it will be understood as embracing 50 such changes in construction and arrangement of the parts as come within the meaning and scope of the appended claims.

I claim:

55 1. A drill stem protector comprising a longitudinally divided cylindrical resilient shoe formed with a plurality of spaced circumferentially extending outwardly projecting bumpers adjacent each end thereof, said shoe having its inner face formed to seat on and conform to the outer periphery of a drill stem, a plurality of independent split clamping bands encircling said shoe adjacent said bumpers, loops on the ends of said bands, and pins insertable in said loops connecting the ends of the bands together; 60 each of said pins being formed with a notch on a margin thereof to receive at least one of said loops in interlocking engagement therewith.

65 2. In a protector for drill stems and the like, a resilient shoe conformable to the circumferential surface of the stem, bumpers on said shoe, a spring clamping band encircling the shoe having loops on its end portions, a pin demountably inserted through said loops; said band and the 70 portions of said shoe encircled thereby being compressed whereby a longitudinal pull is im-

parted to said band tending to spread the ends thereof; and means whereby the pull on the ends of said band will effect interlocking engagement between said band and said pin, said means including a notch in a side edge of said pin arranged to be engaged by a closed end of at least one of the loops on an end portion of said band.

3. In a stem protector, a shoe formed for positioning on a stem, a split clamping band encircling the shoe, a yoke on one end of said band having loops forming the ends thereof, a loop on the other end of said band adapted to be positioned between said yoke loops, and a pin insertable through said loops; said pin being formed with a notch arranged to be engaged by the closed end of said last named loop to hold the pin against removal from said loops, said

notch being in a side edge of said pin and being of a sufficient length to receive the width of said loop.

4. In a structure of the kind described, a body of rubber-like material, said body comprising a cylindrical part which is longitudinally split; an external circumferential band around each end portion thereof, spaced rows of outwardly projecting circumferentially extending bumpers spaced away from said beads, a clamping band occupying each of the circumferentially extending spaces thus provided, and independent fastening means cooperating with the end portions of each of said bands to maintain it in a gripping position in relation to the cylindrical portion of said body.
